PRESSURE REGULATOR FOR THERMOSTAT CONTROL

Filed June 26, 1931

UNITED STATES PATENT OFFICE

ROBERT HETHERINGTON, OF SHARON HILL, PENNSYLVANIA

PRESSURE REGULATOR FOR THERMOSTAT CONTROL

Application filed June 26, 1931. Serial No. 546,949.

My invention relates to conduit shower bath structure, with more particular reference to the regulation of flows at shower heads and while intended for use with any structure to which it may be adapted, is believed to have perhaps its best application to shower heads having an automatic limiting of the shower temperature, for example structure including a thermostatic valve 5 opening the supply to a drainage outlet if or when the supply is undesirably hot for a shower, such as disclosed and claimed in a copending application, Ser. No. 412,814, entitled "Thermostatic control for shower heads".

A purpose of my invention is to provide novel and advantageous detail mechanism for shower heads of the type indicated.

A further purpose is to provide a drainage outlet from a shower head of the type indicated with a combination spring and thermostatic operation, permitting easy adjustments of the valve to operate at different temperatures.

A further purpose is to eliminate danger of improper changing of the setting of a thermostatic opening of a drainage outlet from a shower head by making the setting mechanism inaccessible (as inside the shower head) or nonadjustable, either or both, and optionally as an additional safeguard to make any removal of the setting mechanism lower the temperature of thermostatic opening of the drainage valve.

A further purpose is to provide the inlet to a shower head of the character indicated with selectively different inlet orifices, accommodating the same head to use with widely different supply pressures by using selectively any one of the inlet discs.

A further purpose is to provide the supply pipe to a shower head of the character indicated with pressure control mechanism, permitting wide variation in the supply pressure without incurring any danger of unduly hot water reaching the user of the shower.

A further purpose is to hasten any operation of a thermostat controlling a drainage discharge valve from a chamber having an

overflow discharge to shower outlets by leading the flow that enters the chamber over the thermostat.

Further purposes will appear in the specification and in the claims.

I have preferred to illustrate my invention as applied to a single main form of shower head, with a few only of the many forms of the details to which the present invention is applicable, selecting forms that are practical and efficient in operation and which well illustrate the principles involved.

Figure 1 is a side elevation of a spray nozzle adapted to include detail features embodying a desirable form of my invention, the nozzle being shown in a position of use.

Figure 2 is an enlarged longitudinal section corresponding to a desirable form of the structure of Figure 1.

Figure 3 is a view of the structure shown in Figure 2, looking toward the outlet face of the nozzle into the spray openings.

Figure 4 is a section taken on the line 4—4 of Figure 2 in the direction of the arrows.

Figures 4a, 4b and 4c are similar reduced scale fragments of Figure 4 showing detail modifications.

Figure 5 is a reduced scale, partly sectioned side elevation, corresponding to a fragment of Figure 2, modified with respect to a detail.

Figure 6 illustrates a series of inlet disc orifices for use alternatively at the inlet to the head to accommodate different supply pressures.

Figure 7 is a longitudinal section of a detail,—a pressure control fitting inserted before the nozzle.

Like numerals refer to like parts in all figures.

Describing in illustration and not in limitation and referring to the drawing:—

The embodiment of my invention illustrated in the figures includes a spray nozzle 10 that is connected by a suitable union 11, nipple 12, and pressure control fitting 13 to a hot and cold water supply pipe 14, the nozzle being provided with spray orifices 15, a valved waste pipe 16, and interior connections preventing water from reaching the

spray orifices whenever the temperature of the water in the nozzle reaches any predetermined upper limit beyond which it is considered undesirable for water to discharge 5 through the spray openings.

The nozzle 10 is preferably made of good heat-conducting metal such as brass, with walls that desirably flare outwardly and upwardly and downwardly from an inlet end 10 to the side walls 18 and the upper and lower end walls 19 and 20 of a forward rectangular box-like portion 21 of the nozzle.

The spray plate 22 perforated at 15 to pass the spray is removably mounted upon 15 the open end of the box and carries on its inner side back of the spray openings 15 a light sheet of metal 23 which forms with the main plate 22 a header chamber 24 that opens at the top at 25 into the interior of 20 the box at a high point thereof and is preferably closed from the box except at this high overflow inlet 25.

The spray plate 22 is removable to give easy access to operating structure inside the 25 box, and is shown held to place by suitable screws 26 and sealed against leakage around the joint by a gasket 27.

A drainage outlet port 28 from a low portion of the box 21, includes inner and outer 30 flanges and a central longitudinally perforated hub. The outer flange receives the inlet end of the drainage pipe 16 and the inner end of the inner flange forms a seat for the drainage valve 29 which is carried 35 on a stem 30 having a sliding and guiding support in the perforated hub 31.

The valve 29 is adjustably mounted upon an intermediate point of the stem member 30. The outwardly projecting part of the 40 stem slides in the stationary guide 31, extends through the guide and carries a spring 32 adjustably compressed between the guide and a head 33 on the outer end of the stem.

The inwardly directed threaded portion 45 34 of the stem carries spaced sets of nuts 35 and 36 which are used for making a loose operating adjustable connection with a thermostat 37.

The thermostatic element 37 has one end 50 fastened at 38 to the wall of the box at preferably an intermediate point of the box length whence it extends diagonally upwardly to near the upper end of the box, makes an easy return bend at 39 and extending 55 downwardly presents its free end to make a loose operating connection at 40 with the stem of the valve 29.

As illustrated the thermostatic element is 60 perforated at 40 to pass the valve stem with easy clearance, the sets of nuts 35 and 36 forming abutments carried by the stem on opposite sides of the thermostatic element.

Preferably the abutments 35 and 36 presented by the stem on opposite sides of the 65 thermostatic element are so set that the

thermostatic element holds the valve slightly open at ordinary temperatures when the pressure inside the box is atmospheric.

As soon as a user turns water into the nozzle for use as a spray, the liquid pressure 70 inside the box increases sufficiently to close the valve against the slight opening pull of the thermostat.

If the temperature of the water rises, the force with which the thermostat tends to 75 open the valve progressively increases with the progressive increase in temperature until at the selected high temperature this force is sufficient to overcome the liquid closing pressure upon the inside of the valve, the 80 valve being snapped open by the pull of the thermostat which immediately stops discharge through the spray openings 15, the hot water draining away through the waste outlet. 85

One important feature of the present invention makes the effective resilient opening pull upon the valve at raised temperatures 90 adjustably variant, and with change of settings optionally out of reach of the ordinary user. 95

This permits an authorized individual to readily set the thermostat to open the valve at different desired temperatures and under 100 respectively different pressure conditions 35 within the box, or/and to accommodate different resilient characteristics of the thermostatic element.

The compressive strength of the spring 32 is adjustably varied by longitudinally shifting the valve stem with respect to the valve. 105

Such adjustments effect corresponding changes in the strain of the thermostatic element 37 needed to hold the valve slightly 110 open at ordinary temperatures, and thereby changes the degree of temperature rise 115 needed to merely relieve an initial strain of the element 37.

The adjustable spring pressure upon the 120 valve may preferably tend to either close or open the valve, according to circumstance, as with respect to the temperature at which the valve is to open, the resilient and thermostatic characteristics of the thermostatic element, as well as with respect to pressure 125 conditions back of the valve.

Figure 4 shows the spring 32 adjustably pressing in a direction to close the valve while fragmentary Figure 4a shows the 130 spring 32' adjustably pressing in a direction to open the valve.

When installed in hotels it is particularly desirable that the setting of the thermostat shall be out of reach of transient guests, as otherwise tampering with the setting mechanism by a guest may result in scalding conditions at the shower. 135

The drainage outlet fitting 16 is usually readily removable upon loosening a screw 140

16' and when removed may disclose the spring 32, as in the form of Figure 4.

The spring 32 with hotel conditions of service is usually desirably non-adjustable by guests, at least not adjustable to an extent that may unduly raise the temperature setting of the thermostatic opening of the drainage valve, and in the forms of Figures 4a, 4b and 4c the adjustment can only be made from inside the overflow compartment 21.

In Figures 4 and 4b the spring 32 or 32² is acting in a direction to close the valve 29, and if the spring were taken out, as by the tampering of a transient guest, the valve 29 will either stay open continuously or if it does close responsive to the water pressure within the overflow chamber, the temperature at which the thermostat will open it will be lowered by reason of the absence of the spring.

While the drainage outlet fitting 16 is desirably readily removable from the shower head as by loosening a set screw 16', the front plate 22 of the box is much less readily removable, and is readily fastened to place in a way making it difficult or impossible to take off without special tools, and the illustrated screw fastening at 26 is intended for a conventional illustration of any such fastening.

In the forms of Figures 4b and 4c, the spring is inside the shower head and only accessible by removal of the front plate 22, intended to be difficult or impossible to remove without special tools.

In Figure 4b the spring is made non-adjustable and any removal of the spring will cause the thermostatic opening of the valve at relatively low temperature.

In Figures 4c, 4a and 4 the spring 32³, is provided with an adjustment at 32⁴, 32⁵ or 32⁶ but this adjustment is out of reach of the ordinary hotel guest and permits the management or other authorized person to accommodate easily the variant wishes of different guests as to the maximum shower temperatures, or different pressure conditions at different parts of the hotel.

It will be seen that in both Figures 4b and 4c the spring 32² or 32³ is compressed between the side of the chamber and an abutment on the stem 34 of the valve, the abutment 32⁴ being adjustable in Figure 4c and non-adjustable in Figure 4b.

In Figure 4a the spring is adjustable but out of reach of the ordinary user, it being necessary to not only take off the front plate of the head but also to remove the thermostat before adjustment can be effected.

Another feature of the present invention is directed to the flowing of the inlet water over the thermostatic element even while the box is empty.

As a result of this feature the drainage

valve 29 stays open continuously as long as the supply water is undesirably hot, the box 21 remaining substantially empty above the drainage outlet.

As shown in Figure 2 the inlet end of the nozzle is provided with a centrally perforated inward flange 41. The inlet end of a pipe 42 threads rigidly into the perforation of the flange 41 and the outlet end of the pipe which directs the flow upon the inside surface of the thermostat is located to run the inlet water always over a considerable portion of the length of the thermostatic element, thereby insuring a prompt action of the thermostat irrespective of the quantity of water in the box 21.

If the water first entering the box is unduly hot the opening of the thermostat is thus extremely prompt by reason of the water being directed to flow over the length of the element while the box is still empty.

The form of the member guiding the inlet supply water to the upper portion of the thermostat should be selected to most effectively flow the inlet water over the thermostat 37 without permitting any of it to splash over the sheet 23 into the discharge compartment 24.

In Figure 2 it is shown as a suitably curved nipple 42 while in Figure 5 it includes a spray or baffle member 43 illustrated as an integral portion of a nipple 44 threaded into the flange 41, the member 43 being bent or otherwise formed to best direct the water entering the box to most effectively engage the thermostatic element without any of it entering the discharge compartment 24 except by normal use of the shower.

It will be seen that the liquid pressure inside the nozzle will be determined for a given liquid by the rate of flow into the nozzle and the size and number of the spray openings.

For a given size and number of spray openings and a given size of inlet opening the amount of water entering the nozzle will depend upon the available pressure in the supply pipe 12 which is frequently different in different communities, and I accommodate my nozzle to operate alike on different commercial supply pressures by selectively throttling the nozzle inlet.

As illustrated in Figure 6 a plurality of throttle discs 45 are provided having orifices 46 of progressively different sizes.

Any one of these discs may be inserted as shown in Figure 2 at the inlet end of the nozzle, that disc being selected having a size of orifice that will best accommodate the normal water pressure in the supply pipe 14.

It will be understood these available normal pressures vary quite widely in different localities.

While the water supply pressures will

have quite different though perhaps quite definite maximum pressures in different localities, the available pressures will many times not be constant through the day, the 5 maximum pressures (different in different localities) being usually available at indefinite periods of the day and variably lower pressures at other times of the day.

It will be understood that the thermostat 10 opens the drainage valve 29 against the water pressure within the box 21 and that if the water pressure is unduly high the temperature at which the thermostat opens the valve will be raised in that the thermostat 15 stat must acquire an abnormally great thermostatic strain to overcome the abnormally high pressure.

In view of this the applicant provides a 20 pressure-regulating fitting at 13 which reduces the pressure beyond the fitting to a satisfactorily uniform value irrespective of even quite wide variations of pressure before the fitting, such pressure variation as does take place after the fitting being as a consequence 25 too small to materially affect the temperature at which the thermostat opens the valve.

One form for this fitting is illustrated in 30 Figure 7. The variable water supply pressure at the inlet of this fitting pushes back a spring piston to progressively throttle a discharge opening beyond the piston, thereby securing a sufficiently uniform discharge through the fitting despite variant supply 35 pressure.

A sleeve 13 comprising the body or barrel of the fitting makes threaded connections at its inlet and discharge ends with the pipes 14 and 12.

40 The sleeve 13 has a cylindrical bore 47 inward for a considerable portion of its length from its inlet end, with a throttle opening and an inward shoulder 48 at the inner end of the bore 47 and a forwardly flaring bore 49 from the shoulder 48 toward the outlet end of the fitting.

The pressure-regulating member includes 50 a piston or disc 50 sectionally smaller than the bore 47, within the bore 47, and resiliently pressed away from the shoulder 48 by a spring 51 compressed between the shoulder and disc.

Rearward movement of the disc 50 is illustrated as limited by a forwardly extending 55 stem 52 surrounded by the spring. This stem has a forward taper into the throttle opening, progressively throttles the opening when pushed forwardly and carries a second disc or transverse pin 53 at its forward 60 end limiting rearward movement of the stem and piston by engaging the opposite sides of the bore 49.

When the water supply is turned on the 65 water pressure forces the disc or piston 50 forward along the bore 47, at the same time

moving the forwardly tapering stem further into the throttle opening, progressively throttling at the opening.

The inward movement of the disc 50 against the retractive force of the spring 70 progressively increases with increasing supply pressure at the same time that the spacing between the taper stem 52 and the inside of the sleeve at the inlet of the bore 49 progressively closes.

The water in passing through the sleeve passes between the windings of the spring into the interior thereof and thence onward through the throttling inlet of the flaring bore 49 of the sleeve to the shower head. 80

The strength and dimensions of the spring are selected or adjusted to make the throttling between the taper stem 52 and the contracted portion of the sleeve progressively variant with supply pressure which thereby 85 makes the rate of flow through the fitting affected to only a substantially immaterial extent by relatively wide variations in the applied inlet pressure.

When the spray water is turned on for 90 use at the spray, the first rush of water increases the pressure inside the nozzle and effects a closure of the waste valve.

The box does not fill instantaneously with 95 water due to the inlet flow being throttled at the fitting 13 and at the throttle disc 45.

If the water is too hot for use at the spray the thermostat forces open the waste valve before the box has filled sufficiently to overflow into the orifice header 24, the water 100 falling as soon as the valve opens.

If the temperature of the water is too low to operate the thermostat the water fills 105 the nozzle, overflows into the header compartment and discharges as spray through the openings 15 and if the user inadvertently turns on too much hot water it cannot reach the spray orifices, being diverted to waste before the box overflows or if already full, 110 before the temperature of the spray can become undesirably high.

In view of my invention and disclosure 115 variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what 120 I claim as new and desire to secure by Letters Patent is:—

1. Shower structure of the character indicated including a chamber having an inlet, an overflow discharge to the shower and a low drainage outlet, a drainage valve across the outlet, a thermostat having a considerable portion of its length inside the chamber higher than the outlet and opera- 125 130

tively connected to the valve, means operative with low water in the chamber for directing the inlet water to flow over the high portion of the thermostat and means for automatically adjusting the normal water supply pressure applied to the inlet.

2. Shower structure of the character indicated including an overflow chamber having an inlet, an overflow discharge to the shower and a low drainage outlet, a drainage valve across the outlet, a thermostat having a considerable portion of its length inside the chamber higher than the outlet and operatively connected to the valve and means operative with low water in the chamber for directing the inlet water to flow over the high portion of the thermostat.

3. The structure of claim 2 in which said means includes a pipe inside the chamber having one end threaded into the inlet and the other directed to the thermostat at a high portion thereof.

4. The structure of claim 2 in which said means includes a nipple at the inner end of the inlet and a baffle inside the chamber on the inner end of the nipple.

5. The structure of claim 2 in combination with a pressure control fitting in the inlet for regulating the delivery into the head to maintain it adequately constant irrespective of variation in the supply pressure.

6. The structure of claim 2 in combination with a pressure control fitting in the inlet including a throttle valve spring pressing open and adapted to be partially closed against the retraction of the spring to a progressively greater extent by progressively greater pressure.

40 7. Shower mechanism of the character indicated including a chamber having a low drainage outlet and a high overflow outlet to the shower, a valve across the drainage outlet, a stem adjustably threaded on to the valve, a guide surrounding the stem, a spring around the stem having one end against the guide, a non-adjustable head on the stem engaging the other end of the spring, a thermostat inside the chamber and a longitudinally adjustable connection between the stem and thermostat, the head and spring being outside of the chamber.

8. Shower mechanism of the character indicated including a chamber having a valved inlet, a low drainage outlet and a high overflow outlet to the shower, a valve inside the chamber across the drainage outlet, a thermostat operatively connected to the valve and spring means cooperating with the thermostat holding the valve normally open when the inlet is closed, permitting the water pressure inside the chamber during normal use to hold the valve closed and to permit the thermostat when subjected to abnormally high temperature to open the valve.

9. Shower mechanism of the character indicated including a chamber having a valve inlet, a low drainage outlet and a high overflow outlet to the shower, a valve inside the chamber across the drainage outlet, a thermostat inside the chamber operatively connected to the valve and a spring located in the outlet upon and cooperating with the thermostat whereby the valve normally opens when the inlet supply is closed, whereby the pressure of the water in the chamber during normal use holds the valve closed and whereby the valve opens automatically in the event that the thermostat is subjected to undesirable high temperature from the water of the chamber.
